GAUGE FOR PICTURE FRAME MAT CUTTER

Harold P. Penner, 945 S. Ambridge St.,
Anaheim, Calif. 92806

Filed May 5, 1972, Ser. No. 250,847

Term of patent 14 years

Int. Cl. D10—04

U.S. Cl. D52—6 R

FIG. 1 is a top and rear perspective view of a gauge for a picture frame mat cutter showing my new design;

FIG. 2 is a bottom and rear perspective view thereof;

FIG. 3 is a right side elevational view thereof.

I claim:

The ornamental design for a gauge for picture mat cutter, as shown.
